CLAIM

The ornamental design for a label holder, as shown and described.

DESCRIPTION

FIG. 1 is a bottom, front, left-hand side perspective view of a label holder showing our new design in an environment of use;

FIG. 2 is a top, front, left-hand side perspective view of a label holder shown in an alternate environment of use; FIG. 3 is a bottom, front, right-hand side perspective view of a label holder;

FIG. 4 is a front elevational view thereof;

FIG. 5 is a back elevational view thereof;

FIG. 6 is a top plan view thereof;

FIG. 7 is a bottom plan view thereof;

FIG. 8 is a left-side elevational view thereof; and,

FIG. 9 is a right-side elevational view thereof.

The broken lines immediately adjacent the shaded areas represent the bounds of the claimed design while all other broken lines represent the environment.
